E. C. PENFIELD, OF PHILADELPHIA, PENNSYLVANIA.

Letters Patent No. 88,979, dated April 13, 1869.

IMPROVED TRUSS-PAD.

The Schedule referred to in these Letters Patent and making part of the same.

To all whom it may concern:

Be it known that I, E. C. PENFIELD, of the city of Philadelphia, in the county of Philadelphia, in the State of Pennsylvania, have invented certain new and useful Improvements in "Truss-Pads;" and that the following description, taken in connection with the accompanying drawings, and letters of reference thereon, which form a part of these specifications, sets forth the nature and principles of my improvement, by which my invention may be distinguished from all others of a similar class, which improvements I desire to secure by Letters Patent.

In the accompanying drawings—

Figure 1 represents a back elevation of a truss, showing my improvement applied thereto.

Figure 2 is a longitudinal vertical section of the same, taken on the line x x , fig. 1.

Figure 3 represents a face view or plan of the lever-bar, or tongue.

The object of this invention is to afford more certain means of fastening and holding a truss-pad in whatever position it may be set.

Heretofore it has been fastened by various arrangements of devices, in such a manner as to have its inclination varied at pleasure, and especially by means of levers and set-screws acting upon a universal or "ball-and-socket joint," so as to bind the ball and its socket together; but it is well known that by these methods of fastening it is not secure, on account of the slipping of the ball upon the smooth surface of the socket. This difficulty I overcome by my improvement.

To enable others skilled in the art to make and use

my invention, I will proceed to describe its construction and operation.

In the drawing—

A represents the body-spring plate, with an arm, B, attached in the ordinary manner.

On the end of the arm B is the ball C, made to fit in a socket, d, formed in the plate e.

A lever-tongue, or bar, f, (see fig. 3,) having an opening, i, is attached to the plate e, by means of the screw g.

At the other end of the lever-bar f is a set (thumb) screw, H, passing through the plate e and lever-tongue f. By means of this set-screw H, the lever-bar f forces the ball C into the socket d, or relieves it from said socket.

In the lever-bar f, I form a projecting ridge or ring around the opening i, having an acute edge, which, by coming in contact with the ball C, will firmly bind and hold upon the periphery of the ball C, and prevent its slipping in the socket d, thereby securely holding the truss-pad in any desired position.

Having thus described the nature and construction of my invention,

What I claim as new, and desire to secure by Letters Patent, is—

The combination, hereinabove described, consisting of a ball-and-socket (or universal) joint, and the lever-tongue, (or bar) having an acute angular edge, for the purpose of securely binding and holding, substantially as and for the purpose herein set forth.
